UNITED STATES PATENT OFFICE.

ELMER SPIRES, OF COFFEYVILLE, KANSAS.

WAGON-BRAKE.

SPECIFICATION forming part of Letters Patent No. 629,017, dated July 18, 1899.

Application filed November 22, 1898. Serial No. 697,129. (No model.)

To all whom it may concern:

Be it known that I, ELMER SPIRES, a citizen of the United States, residing at Coffeyville, in the county of Montgomery and State of Kansas, have invented certain new and useful Improvements in Wagon-Brakes; and I do declare the following to be a full, clear, and exact description of the invention, such as will enable others skilled in the art to which it appertains to make and use the same.

My invention relates to improvements in wagon-brakes; and the object is to provide a simple, effective, and durable device of this character.

15 To this end the invention consists in certain features of construction and combination of parts, which will be hereinafter fully described, and particularly pointed out in the claim hereto appended.

20 In the accompanying drawings the same reference characters indicate the same parts of the invention.

In said drawings, Figure 1 is a side elevation of my improved wagon-brake. Fig. 2 is 25 a transverse section on the line 2 2 of Fig. 1. Fig. 3 is a plan view.

I designates the usual hand-lever fulcrumed on the side of the wagon-body and carrying the usual latch-bar 2, which coacts 30 with the notched segmental rack 3. 4 designates a coupling-rod extending from said hand-lever to the upper end of a brake-lever 5, which is formed on one end of a transverse shaft 6, journaled in suitable bearings fixed

35 to the under side of the hounds. This shaft is also provided with two depending arms 7 7, from which rods 8 8 extend to the parallel arms 9 9 on the brake-shaft 10, journaled in suitable bearings on the transverse beam 12,

supported by plate-brackets 13 13, suspended 40 from a corresponding beam 14, extending across the hounds and secured to the wagon-body by the chains 15 15. The outer ends of this brake-shaft 10 are turned upwardly to form the crank-arms 16 16, which terminate 45 in lateral pins 17 17, on which are mounted the brake-shoes 18 18. From this construction it will be seen that a forward movement of the hand-lever applies the brake and a reverse movement releases it.

50 Although I have specifically described the construction and relative arrangement of the several elements of my invention, I do not desire to be confined to the same, as such changes or modifications may be made as 55 clearly fall within the scope of my invention without departing from the spirit thereof.

Having thus fully described my invention, what I claim, and desire to secure by Letters Patent, is—

60 In a wagon-brake, the combination with the parallel beams 12 and 14 suspended from the wagon-body, of the brake-shaft 10 journaled on said beam 12 and provided with the arms 9 9 and 16 16, the latter carrying the brake- 65 shoes, and the shaft 6 journaled in suitable boxes fixed to the hounds and formed with the depending arms 7 7 operatively connected to the alined arms 9 9 on the brake-shaft, substantially as shown and described.

70 In testimony whereof I have hereunto set my hand in presence of two subscribing witnesses.

ELMER SPIRES.

Witnesses:

MILLARD F. WILLIAMS,
PERRY CUMMINGS.
